UNITED STATES PATENT OFFICE.

EDWARD L. MAYBERRY, OF LOS ANGELES, CALIFORNIA.

SYSTEM OF ARCH-RIB FLOOR CONSTRUCTION.

1,391,748.

Specification of Letters Patent. Patented Sept. 27, 1921.

Application filed December 22, 1915. Serial No. 68,187.

To all whom it may concern:

Be it known that I, EDWARD L. MAYBERRY, a citizen of the United States, residing at Los Angeles, in the county of Los Angeles 5 and State of California, have invented a new and useful System of Arch-Rib Floor Construction, of which the following is a specification.

This invention relates to the construction 10 of concrete floor systems having series of arches, and an object of the invention is to produce a mold or form which can be erected and taken down in minimum time.

Other objects and advantages may appear 15 in the subjoined detailed description.

The accompanying drawings illustrate the invention:

Figure 1 is a vertical section of a fragment of floor system and form constructed 20 in accordance with this invention.

Fig. 2 is a perspective view of a portion of Fig. 1, the flexible soffit form-plate of only one of the arches being shown.

Fig. 3 is a vertical section on line indicated by x^3-x^3 , Fig. 1.

There are provided shoring timbers or posts 1 having their lower ends supported on whatever supporting structure is available and having their upper ends in engagement 30 with the under faces of main beams or girders 2. The main beams 2 support on their upper faces transversely extending impost beams 3 which may be solid and which constitute the bottom form members for the 35 rib portions 4 of the arch rib floor system 5. The open side of the channeled beams is on top. Supported by and between adjacent transverse beams 3 are flexible soffit form plates 6 having their opposite ends detachably connected to the impost beams 3, and for this purpose said ends may be inserted between the sides of the impost beams 3 and clamping strips 7 as in Fig. 1, said strips being held by bolts 8 passing therethrough and through said impost beams.

The soffit form plates 6 are longer than the spaces between adjacent impost beams 3 so as to arch or curve above the level of the horizontal molding face a of the impost 50 beams 3, and said plates are each formed of one or more thin sheet metal plates which may have their surfaces plain as in Fig. 4 or may have portions of their molding surfaces in relief or intaglio as, for example, 55 provided with depressions and projections

11, 12 forming corrugations as in Figs. 1 and 2. By corrugating the plates they may be made of thinner stock for a given strength than if they are uncorrugated, and the completed soffit of the arch will thus be molded 60 with corrugations or projections and depressions corresponding to the depressions and projections 11, 12 of the soffit form plates. Each soffit plate 6 may be of sufficient size so that each floor arch 13 will be molded 65 on a single plate or, as shown, each plate may be formed by a number of sections having abutting edges, and said sections may each comprise a single plate or sheet of standard or stock size.

At the joints 13 between the adjacent sections of the soffit form plates 6, if said plates are in sections, and at any other desired points there are provided curved soffit-plate supports which, as shown, may be formed 70 in like sections 14, 15 fastened together by any suitable means as, for instance, cleats 16 and nails 17. The soffit plate supports 14, 15 are provided with angular notches 18 to engage the clamping strips 7, as in Fig. 80 1, so as to be supported in position thereby.

At the ends of the soffit plates 6 there are provided curved end form plates 19 provided at their ends with angular notches 20 to fit the impost beams 3.

Supported on the impost beams 3 are form plates 21 adjacent the bottom margins of the end plates 19, and extending downward from the inner margins of said plates 21 are girder form side plates 22, there being at the 90 lower margins of said side plates 22 bottom plates 23. The plates 22, 23 rest on transverse beams 24 engaged by shoring timbers or posts 25.

The form as above described will be 95 erected in place and then a suitable concrete mixture will be poured upon the impost beams 3, soffit plates 6 and girder plates 21, 23. When the concrete of the floor structure has stood the prescribed or desired length of 100 time for hardening, the soffit plates 6 will be detached and removed and then the other members of the form will be taken down and removed.

From the foregoing it is seen that the 105 soffit plates 6 form arches extending above the level of the molding face of the impost beams 3 and that the rib portions 4 may be made of relatively great depth so that a monolithic structure having relatively long 110

and wide concrete arches can be constructed of sufficient strength to withstand heavy live loads.

I am aware that it is not new to employ a flexible soffit form plate in combination with the metal beams forming permanent parts of the structure, but the novel combinations in the appended claims are new and are of advantage in the construction of a monolithic floor system for the reason that any depth of ribs relative to the depth of the arches at their crowns can readily be obtained.

If it is desired to make provision for suspending a ceiling from the floor construction, suitable anchors 26 of wire or equivalent may be inserted and clamped between some of the clamping strips 7 and their impost beams 3, as in Fig. 1.

In casting reinforced concrete structures, it is quite essential that the temporary form members be securely connected to one another so as to prevent yielding of the forms during the pouring operation and while the setting of the concrete is in progress, and this is especially true in the casting of floors. I secure the necessary rigidity of the floor forms by the particular construction, arrangement and combination of elements shown in the drawings, wherein the clamping strips 7 perform the two-fold function of firmly clamping the side margins of the soffit form plates 6 between the strips and the impost beams 3, and taking the lateral thrust of the supports 14, 15. The greater the load imposed on the form plates 6, the

greater will be the lateral thrust of the supports 14, 15 against the clamping strips 7 which, consequently, hold the side margins of the soffit form plates the more tightly and thus prevent buckling of those portions of the soffit form plates lying between adjacent pairs of supports 14, 15.

I claim:

1. In combination, impost beams, transverse bolts extending through said beams, flexible metal arch plates having their lower edges resting upon said bolts, clamp strips engaging over the bolts, soffit plate supports fitting the under-side of the arch plates and notched to fit the outer upper corners of the clamp strips, and clamp means coöperating with the bolts to clamp the marginal edges of the plates between the impost beams and the clamp strips.

2. In combination, impost beams, flexible metal plates forming arches extending above the level of the upper face of the impost beams, clamping strips extending along the impost beams, the lower edges of the metal plates being inserted between the clamping strips and impost beams, soffit-plate supports having their ends resting on and thrusting laterally against the clamping strips and fitting the under side of the metal plates, means detachably fastening the clamping strips to the impost beams, and means detachably supporting the impost beams.

Signed at Los Angeles, California.

EDWARD L. MAYBERRY.
